FOLDABLE FIBERBOARD EGG CASE

Kenneth C. Ferguson, Indianapolis, Ind., assignor to Inland Container Corporation, Indianapolis, Ind., a corporation

Application November 1, 1943, Serial No. 508,505

2 Claims. (Cl. 229—27)

1

This invention relates to a light weight covered egg case.

This application is a continuation-in-part of the copending application Serial No. 484,333, filed April 24, 1943, and entitled "Egg case and method of handling eggs," now Patent No. 2,365,182.

Said application, in addition to disclosing methods of handling eggs utilizing a covered case or parts thereof, also discloses a case that requires no staples to erect or assemble same, a case wherein the ends are of multiple ply or thickness, wherein the sides are reenforced by liner means, wherein the central transverse partition is formed by the liner means, the central partition supporting the cover intermediate the ends thereof, wherein the liner means and case proper may be apertured for ventilation, the apertures registering for the latter purpose and non-registering when one or the other aforesaid is inverted or turned end for end for non-ventilation, and a case wherein the cover is locked to the case.

All of the aforesaid features therein disclosed are also retained in the present disclosure.

The chief object of the present invention is to provide a multirip case embodying all the aforesaid features plus the desirable objective that the case when closed is substantially devoid of all protuberances or projections, so that side or end contact will be substantially of facial and not localized in character.

Herein the case may be of three or four piece construction, as is the case disclosed in the copending application.

Other objects and features of the invention will be set forth more fully hereinafter.

The full nature of the invention will be understood from the accompanying drawings and the following description and claims:

In the drawings,

Fig. 1 is a longitudinal central sectional view of the covered egg case embodying the invention, the flats, fillers and partitions being omitted therefrom.

Fig. 2 is a top plan view of the covered case.

Fig. 3 is a transverse central section.

Fig. 4 is a plan view of the cover blank.

Fig. 5 is a plan view of the partition and sidewall blank.

Fig. 6 is a plan view of the box proper blank.

In the drawings 10 indicates the bottom, 11 the sidewalls and 12 the end walls and integral with each side edge of each side wall is a wall forming portion 13. These portions at opposite ends of the case lap each and lie inside the end wall 12. Each

2

of said portions 12 and 13 are apertured, the apertures registering to form hand holes 14 in the end of the case. The stock of the hand hole 14 in the end wall is turned inwardly as at 15 and upwardly as at 16 and forms a smooth upper bearing in the hand hole 14 and serves to lock portions 12 and 13 together.

The top of wall 12 is turned inwardly as at 17 and forms a smooth top bearing for the end wall 10 structure. Flap or tongue 18 extends downwardly and inwardly and laps the upper end of the adjacent innermost portion 13. This also constitutes an end wall structure lock, same being maintained by the cover, although, if desired, but shown herein, the tongue 16 may bear outside of same for locking purposes. If desired, this tongue 18 may be long enough to lap tongue 16, as shown in Fig. 7 of the aforesaid application.

20 Herein the central partition structure includes a pair of walls 20 of case width and depth. These may be joined together at their bottom edges as at 21, thereby distinguishing from upper junction as shown in Figs. 1 and 2 of said copending application.

Extending outwardly from each side edge of partition 20 is the sidewall reenforcing portion 22. Each at its outer side edge includes an in-turned flap 23. The two confronting flaps 23, see 30 Fig. 1, are retained by the downturned tongue 18 on the end wall.

Hence, the partition is locked to the case. Observe that the space between adjacent side edges of flaps 23 is at least as great as the width of the hand hole. Should, however, necessity demand a four, five or six ply end wall, the tongue 18 may be extended downwardly and hand hole apertured and/or either or both of the flaps 23 may be extended laterally for full end width and hand hole 40 apertured. The foregoing interlocking construction permits of extension for further or additional ply wall construction when desired.

Each side wall 11 at its upper edge includes an in-turned flap 19, longitudinally coextensive with 45 the sidewall, except at the immediate ends thereof. These flaps rest upon the partitions 20 near their sides and overlie and rest upon the upper edges of sidewall portions 22 and serve, when the case is closed, etc., to retain the partition structure in position.

Note that each of the partition portions 20 are apertured at 24 and these apertures register. Sidewalls 11 include apertures 25 and sidewalls 22 include apertures 26. When registered case ventilation results, when either is turned end for end,

the apertures do not register and ventilation is prevented. In this respect the partitioned case herein is similar to that disclosed in Fig. 1 of the aforesaid application and has the same objectives and advantages.

In Figs. 1 to 3, the cover includes two major portions 21. Adjacent ends are provided with depending portions 28 united at their lower ends as at 29. As shown in Fig. 1, the reversely folded portions 28 are nested between adjacent partitions 20.

Each portion 21 overlies the flaps 19 and bears thereon. Each portion 21 at its remote end terminates in a depending tongue 30 that is adapted to be tucked downwardly and inwardly between the adjacent side edges of flaps 19 and tongue 18 for cover locking. Each portion 21 adjacent tongue 30 has a finger hole 31 to facilitate opening the cover.

Observe central depending portions 28 are not 20 as wide as portions 21 and that each portion 28, adjacent its connection to top portion 21 is notched as at 32. After the box has been assembled and locked by the end wall flaps 18 it may be filled. Then flaps 19 are elevated to permit 25 nesting of cover portions 28 between the partitions 20. When nearly fully nested the flaps 19 are infolded and seat in notches 32, thereby locking the cover to the box with portions 21 of the cover overlying flaps 19 now held down by the 30 cover. The shortening of the length of flaps 19 permits the cover tongues 30 to fit between the end flaps 18 and the side edges of flaps 13 when the box or case is closed, thus constituting another lock.

The foregoing structure permits of ready access to the case contents for sampling, candling, grading, etc. A case of this character, when made of corrugated board, by way of example, is capable of repeated reuse. Use of egg flats, fillers, etc., 40 reinforce the top and bottom. The partition structure herein, and case proper formation provide for multiple wall construction.

The several advantages set forth in the co-pending application, naturally, likewise, are included herein together with the advantage herein that no portion of the case projects beyond the wall outlines and cover.

While the invention has been illustrated and described in great detail in the drawings and 50 foregoing description, the same is to be considered as illustrative and not restrictive in character.

The several modifications described herein, as well as others which will readily suggest themselves to persons skilled in this art, all are considered to be within the broad scope of the invention, reference being had to the appended 55 claims.

The invention claimed is:

1. An egg case structure including in combination a one-piece case having independent downwardly directed and inturned locking tongues at 60

a pair of opposite sides, dual partitions immediately adjacent each other and substantially parallel to and intermediate said sides, lateral extensions on the partitions parallel to and coextensive with the other pair of sides, flap ends on said extensions retainable in first mentioned side contact by said tongues, a cover for the case having a midportion nestable between the partitions and end portions in frictional engagement with the locking tongues, and inwardly directed flaps on the top edges of the said other pair of sides and overlying the partitions adjacent thereto, the cover bearing on said last mentioned flaps, the nested portion of the cover being notched for last mentioned flap reception for cover retention.

2. A covered case structure including a one-piece blank including a bottom, sidewalls integral therewith, end walls integral with the bottom, flaps on the upper edges of the sidewalls and directed towards each other and substantially coplanar when the case is erected, flaps on the side edges of the sidewalls and directed angularly thereof and positionable adjacent the adjacent end wall, tongues on the upper edges of the end walls and directed inwardly and thence downwardly for sidewall retention and case formation, and a one-piece blank cover including an intermediate reversely folded case receivable portion, adjacent cover forming portions bearable on the first mentioned flaps, and tongues at the free ends of the cover for case insertion between the side edges of the first mentioned flaps and end wall tongues, at least one of the first mentioned sidewall flaps and reversely folded portion of the cover being notched for the interlocking association of the other for cover retention.

KENNETH C. FERGUSON.
